UNITED STATES PATENT OFFICE.

ALLEN BURNAM, OF SAN ANTONIO, TEXAS, ASSIGNOR OF ONE-HALF TO C. M. HOCKER,
OF SAN ANTONIO, TEXAS.

AIR PUMP.

1,414,621.

Specification of Letters Patent.

Patented May 2, 1922.

Application filed November 19, 1920. Serial No. 425,179.

To all whom it may concern:

Be it known that I, ALLEN BURNAM, citizen of the United States, residing at San Antonio, in the county of Bexar and State 5 of Texas, have invented certain new and useful Improvements in Air Pumps, of which the following is a specification.

This invention relates to an improved air pump particularly designed for inflating 10 pneumatic tires and has as one of its principal objects to provide an efficient and structurally simple pump which will be double acting.

The invention has as a further object to 15 provide a pump employing a single cylinder and a single discharge pipe and wherein an improved valve mechanism will be employed for alternately cutting off communication between one end of the cylinder and the adjacent end of the pipe and coincidentally establishing communication between the other end 20 of the cylinder and the other end of the pipe.

And the invention has as a still further object to provide a pump employing opposed 25 discharge valves for controlling communication between the cylinder and discharge pipe, wherein said valves will be normally held closed by a spring common to both thereof, and wherein movement of either 30 valve to open position will serve to increase the tension of the spring against the other valve for binding the latter valve closed.

Other and incidental objects will appear hereinafter.

35 In the drawings:

Figure 1 is a side elevation of my improved pump.

Figure 2 is a vertical sectional view showing the piston on the down stroke,

40 Figure 3 is a vertical sectional view showing the piston on the up stroke,

Figure 4 is a transverse section on the line 4—4 of Figure 3, looking in the direction of the arrows, and

45 Figure 5 is a detail elevation showing one of the discharge valves employed.

In carrying the invention into effect, I employ a pump base 10 into which is threaded a cylinder 11. At one side of the 50 cylinder, the base is formed with a valve chamber 12 at the lower end of which is a seat 13 and establishing communication between the valve chamber and the cylinder is a passage 14. Surrounding the valve 55 chamber is an upstanding nipple 15.

Threaded upon the upper end of the cylinder is a head or cap 16 provided axially with a depending sleeve 17 and slidably through said sleeve is a hollow piston rod 18, a gland 19 being threaded into the head to surround 60 said rod. Removably mounted upon the lower end portion of the rod is a piston 20, the leathers of which are formed to coat with the wall of the cylinder and threaded upon the lower end of the rod below said 65 piston is a tubular valve cage 21 which carries, near its lower end, a cross pin 22. Freely movable within the cage to seat against the lower end of the rod is a valve 23 movable to open position sustained by the 70 cross pin. Formed through the head 16 is an air inlet passage 24 and slidably surrounding the sleeve 17 is a valve 25 movable to overlie said passage, the valve being normally held closed by a spring 26 surrounding the sleeve. 75 As will be observed, this spring, as well as the valve, is removably held in position by a nut 27 threaded upon the lower end of the sleeve. The valve preferably comprises a 80 metallic ring and overlying said ring is a fiber or other approved washer for sealing the passage 24, the ring and washer loosely fitting the sleeve 17. Removably fitted upon the upper end portion of the piston rod is a handle 28 below which is a suitable stop 85 nut while above the handle is arranged a hollow stop cap 28' which is threaded upon the rod and provided with suitable perforations in the side wall thereof, the cap serving, of course, to removably hold the handle 90 in position. Depending from the head 16 at one side of the cylinder 11 is a nipple 29 alining with the nipple 15 of the base 10 and surrounding a valve chamber 30 within the head. At the lower end of this chamber is 95 a seat 31 and leading through the head from said chamber is a passage 32 establishing communication between the chamber and the cylinder. Fitting at its ends in the nipples 15 and 29 is a discharge pipe 33 at the end 100 portions of which are glands 34 threaded upon said nipples, and threaded into the pipe at a point substantially midway between the ends thereof is a discharge nipple 35 to which is detachably connected a discharge hose 36. 105 This hose may be equipped at its free end with any approved connection for engagement with the casing of a tire valve. Loosely fitting in the discharge pipe 33 is a helical spring 37 extending from end to end of the 110

pipe to project into the valve chambers 12 and 30 and mounted upon the ends of said spring are companion discharge valves which, for convenience, are numbered 38 and 39 respectively. As shown in detail in Figure 5 of the drawings, the valves 38 and 39 are cylindrical for the major portion of their length and are provided with spheroidal or rounded outer ends, the inner end portions of said valves being tapered. Formed in the peripheries of the valves are helical grooves and, as will be observed, the convolutions of the spring 37 at the end portions of said spring, engage in said grooves, the spring surrounding and gripping the valves for securely holding the valves thereon. Thus, as will be seen, the spring will normally hold the valve 38 closed in engagement with the seat 31 and also coincidentally hold the valve 39 closed in engagement with the seat 13.

Assuming now that the pump piston is, as shown in Figure 2, moving downwardly, it will be seen that the valve 25 will move to open position so that air will be admitted 25 behind the piston through the inlet passage 24 while the valve 23 will close against its seat. Accordingly, air in the cylinder below the piston will be forced through the passage 14 into the valve chamber 12 so that the valve 30 39 will be opened. Opening movement of this valve will serve to increase the upward tension of the spring 37 for binding the valve 38 closed so that the air will be discharged 35 through the nipple 35 and hose 36. Upon upward movement of the piston, as shown in Figure 3, the valve 23 will move to open position for admitting air below the piston

through the piston rod 18 while the valve 25 will close. Air within the cylinder above the piston will accordingly be forced through 40 the passage 32 and through the valve chamber 30 for opening the valve 38. Opening movement of this valve will serve to increase the downward tension of the spring 37 for binding the valve 39 closed. Accordingly, 45 like when the piston is moving downwardly, air will be discharged through the nipple 35 and hose 36. It will thus be seen that the pump is double acting. Further, it will be noted that while the spring 37 will normally hold both of the valves 38 and 39 closed, the structure is such that the opening movement of either valve will serve to increase the tension of the spring against the other valve for binding the latter valve closed. Leakage past 50 the discharge valves will accordingly be effectively prevented.

Having thus described the invention, what is claimed as new is:

An air pump including a cylinder, a piston 60 reciprocable therein, means controlling admission of air at opposite sides of the piston, a discharge pipe in communication with opposite end portions of the cylinder, discharge valves associated with said pipe controlling 65 flow in opposite directions therethrough and provided with peripheral grooves, and a spring extending between said valves and at its end portions encircling the valves engaging in said grooves, the spring normally 70 holding the valves closed.

In testimony whereof I affix my signature.

ALLEN BURNAM. [L.S.]
